(57) **CLAIM**

The ornamental design for a cup lid with two drinking structures, as shown and described.

DESCRIPTION

FIG. 1 is front elevation view of a cup lid with two drinking structures, showing our new design;

FIG. 2 is a rear elevation view thereof;

FIG. 3 is a left side elevation view thereof;

FIG. 4 is a right side elevation thereof;

FIG. 5 is a top plan view thereof;

FIG. 6 is a bottom plan view thereof;

FIG. 7 is a rear, left side, and top perspective view thereof;

FIG. 8 is a front and top perspective view of an alternative configuration of the cup lid with two drinking structures, when one drinking structure is in an opening state; and, FIG. 9 is a left side and bottom perspective view of the cup lid with two drinking structures from FIG. 1.

The broken lines depict environmental structure and form no part of the claimed design.

1 Claim, 9 Drawing Sheets
